UNITED STATES PATENT OFFICE

LOUIS M. LEVERONE, OF ALLSTON, MASSACHUSETTS

DESIGN FOR A SHOE

Application filed June 9, 1932. Serial No. 44,032. Term of patent 3½ years.

To all whom it may concern:

Be it known that I, LOUIS M. LEVERONE, a citizen of the United States, residing in Allston, in the county of Suffolk, and State of Massachusetts, have invented a new, original, and ornamental Design for Shoes of which the following is a specification, reference being had to the accompanying drawing, forming part thereof.

Fig. 1 is a view in side elevation and Fig. 2 is a plan view of a shoe showing my new design.

The dominant feature of the design is the

ornamental effect produced by the converging straps at the tip and at each side of the quarter which appear to be attached to converging straps which extend from the shoe bottom over the vamp and from the top and bottom over the quarter.

I claim:

The ornamental design for a shoe as shown and described.

In testimony whereof, I have signed my name to this specification.

LOUIS M. LEVERONE.
